UNITED STATES PATENT OFFICE.

DANIEL RAYMOND SEARLES, OF TIFFIN, OHIO.

VULCANIZER.

1,139,284.

Specification of Letters Patent.

Patented May 11, 1915.

Application filed July 30, 1913. Serial No. 781,960.

To all whom it may concern:

Be it known that I, DANIEL RAYMOND SEARLES, a citizen of the United States, residing at Tiffin, in the county of Seneca and 5 State of Ohio, have invented certain new and useful Improvements in Vulcanizers, of which the following is a specification.

My invention relates to vulcanizers, and more particularly to that class of portable 10 vulcanizing apparatus which is adapted for the repairing of either the inner tubes of tires, or the casings or shoes thereof, and is particularly designed with the view to combining efficiency, lightness and cheapness of manufacture.

The object of my invention is the provision of a portable vulcanizer which shall be safe and reliable, and one which is especially adapted for use in emergency.

20 A further object of my invention is to provide a simple apparatus which will require the exercise of but little skill in the use thereof, and which may be readily and quickly applied to the article to be vulcanized.

25 A further object of this invention is to provide a vulcanizer having heat distributing members so located therein as to produce the maximum of heat from the use of a comparatively small quantity of liquid fuel.

With these and other objects in view my invention consists in the peculiar arrangement and combination of the various parts of a portable vulcanizer as hereinafter described and more particularly set forth in the appended claims.

In the accompanying drawings, wherein the same reference numerals indicate like parts wherever used, Figure 1 is a perspective view of the apparatus; Fig. 2 is a longitudinal vertical section through the device, showing the same in operative position upon an inner tube of a tire; Fig. 3 is a top plan view, and Fig. 4 is a bottom plan view.

45 The device comprises two members 5 and 6, each provided with an enlarged central portion, the central portion of the upper member 5 forming a chamber 7, open on its upper face as shown, and forming a cup-shaped fuel receiving chamber. Within said cup member 7 are formed a plurality of arc-shaped baffle-plates 8, 9, 10, 11 and 12. These plates are so constructed that the interior surface of each forms a shell-like cup 50 which is adapted to receive the liquid placed

within the cup member 7. The walls of the cup member 7 incline inwardly, toward the top of the cup, in such manner as to overlap the baffle-plates, and to form a cup having a well defined shoulder 13 at its upper 60 open end. The bottom of the cup member 7 is concaved, as at 14, in order to conform to the shape of the material to be vulcanized. Extending outwardly from the cup member 7 are wing members 15, 16, provided with 65 open eyes 17, 18. The lower member 6 comprises a central portion 19 having outwardly extending wings 21 and 22 corresponding to the wings 15 and 16 of the upper member. The central portion 19 of the lower member 70 6 is convexed to fit the concavity 14 of the upper member, and the faces 22 and 23 are ground to a polished fit. Removably or otherwise secured in the wings 21 and 22 are bolts 23 and 24, adapted to engage the open 75 eyes 17 and 18 and to be held in place therein by means of wing nuts 25, 26.

The lower member 6 is provided with a series of ribs 27, 28, 29 and 30, which mark off corresponding depressions in the bottom 80 face thereof.

The operation of my device is as follows: The tube or member to be vulcanized is placed, as shown in Fig. 2, at 31, between the members 5 and 6, and a patch represented at 32 placed over the hole or slot in the tube, in such manner that the patch is directly under the concave 14 of the cup 7 of the upper member 5. Any suitable liquid, such as gasoline, alcohol, etc., is now poured 85 within the cup shaped member 7 and circulates about the baffle plates 8, 9, 10, 11, 12, as heretofore explained. The wing nuts 25-26 are then tightened so that the two members are brought as close together as 90 possible to compress the tube and the patch between them. The fluid within the cup 7 is now ignited and allowed to burn for a period sufficient to cause the parts 31 and 32 to vulcanize together by the action of the 95 heat radiated from the plates 8, 9, 10, 11 and 12, down through the concaved bottom 14 and onto the patch and tube 32 and 31. The wing nuts 25 and 26 now being loosened the device may be taken apart and packed away. 100

A peculiar advantage of this device lies in the construction of the baffle-plates 8, 9, 10, 11, 12. It will be noted that these plates are arc-shaped and form cup-like members, as heretofore stated. These plates are 110

graded in size and curved in order to give the greatest possible amount of radiating surface.

I realize that considerable variation is possible in the details of construction herein shown, and I do not intend to be limited thereto, except as pointed out in the appended claims, in which it is my intention to claim all of the novelty inherent in the 10 structure described as broadly as is permitted by the state of the art.

What I claim as new and desire to secure by Letters Patent is:

1. In a vulcanizer, a base member recessed 15 on its under side and having an upwardly convexed central portion and wings extending therefrom, and an open upper member forming a liquid fuel-chamber and having a concaved bottom adapted to fit over the 20 convex central portion of said lower member, wings extending from said upper member, and means for releasably securing the

wings of said upper and lower members together, the lower ends of said securing means being housed in the recessed under 25 side of said lower member.

2. In a vulcanizer, a base-member, an open hollow upper member adapted to fit over said base-member and having its wall inwardly converging toward said opening, 30 the edge of the wall surrounding the opening overhanging the base portion of said upper member, and a plurality of arc-shaped heat-conducting plates arranged within said upper member, the inwardly 35 converging wall of said upper member extending beyond the outer ends of said plates.

In testimony whereof I affix my signature in presence of two witnesses.

DANIEL RAYMOND SEARLES.
